United States Patent Office

Des. 191,559
Patented Oct. 10, 1961

191,559

INCINERATOR

Bernard E. Mustee, Westlake, Ohio, assignor to E. L. Mustee & Sons, Inc., Cleveland, Ohio, a corporation of Ohio

Filed Aug. 1, 1960, Ser. No. 61,574

Term of patent 14 years

(Cl. D81—1)

FIG. 1

FIG. 2

FIG. 3

FIGURE 1 is a perspective view of the front and one side of an incinerator showing my new design;

FIGURE 2 is a top plan view thereof; and,

FIGURE 3 is an elevational view of the side opposite that shown in FIGURE 1.

The dominant features of my design reside in the full line portions thereof.

I claim:

The ornamental design for an incinerator, as shown and described.
